(57) **CLAIM**

The ornamental design for a combined automotive radio receiver, tape player and recorder with built-in microphone, as shown and described.

DESCRIPTION

FIG. 1 is a front elevational view of the combined automotive radio receiver, tape player and recorder with built-in microphone of the present invention;

FIG. 2 is a rear elevational view of the combined automotive radio receiver, tape player and recorder with built-in microphone of FIG. 1;

FIG. 3 is a left side elevational view of the combined automotive radio receiver, tape player and recorder with built-in microphone of FIG. 1;

FIG. 4 is a right side elevational view of the combined automotive radio receiver, tape player and recorder with built-in microphone of FIG. 1;

FIG. 5 is a top plan view of the combined automotive radio receiver, tape player and recorder with built-in microphone of FIG. 1; and,

FIG. 6 is a bottom plan view of the combined automotive radio receiver, tape player and recorder with built-in microphone of FIG. 1.

The broken lines showing of a number in FIG. 1 is for illustrative purposes only and form no part of the claimed design.
